PULLEY HANGER

James A. Anderson, Muskegon, Mich., assignor to Bremerman-Hartshorn, Inc., Cincinnati, Ohio, a corporation of Ohio

Filed Aug. 7, 1961, Ser. No. 129,635
6 Claims. (Cl. 160—133)

This invention relates to a pulley hanger and is more particularly directed to a hanger for use with a slat blind porch shade, although certain of the novel features are not necessarily limited in their application to slat porch shades.

The slat blinds with which the invention is principally employed are of the type having a number of vertically aligned horizontal slats interwoven and connected together by string. A head bar is secured to the uppermost slat and provides a hanging support for the blind. A single pulley mounted at one end of the head board and a double pulley having a cord lock dog mounted in the other end of the head bar cooperate with a draw cord which passes through both pulleys and around the complete blind at both sides of the blind. Pulling on the cord shortens the loops around the blind at each side and causes the blind to roll up from its bottom edge.

The hanger pulley of the present invention combines the functions of a pulley to be mounted to the head bar and a hanger for the complete assembly. As such it is desirable that the hanger pulley be easy to apply to the slat blind and easy to accommodate to the supporting structure to which the slat blind is to be mounted. Further, it is desirable that the device be provided with means for preventing, insofar as possible, the fouling of the draw cord. Still further, the device should be of ruggedest construction with its parts so related and oriented as to assure regularity of the cord drawing and locking functions to the end that minimal ingenuity is required to adjust the blind to the proper level.

An important feature of the invention resides in the ease with which the hanger pulley can be applied to a slat blind with provision for wide variation in the longitudinal position along the head bar to which the hanger pulley is affixed. More specifically, it has been an objective of the invention to provide for the securing of the pulley to the slat blind head bar by sliding an upwardly projecting plate between the head bar and an overlying slat and wrapping a free end of the draw cord about that portion of the plate which projects above the head bar.

Another objective of the invention has been to provide a slot of a particular shape formed in opposed side edges of the upwardly projecting plate, the shape of the slot being such as to facilitate the application of the cord to the plate and to impede its inadvertent removal. The invention provides a cooperative relation between the slots and the configuration of the hanger which locks the hanger against twisting or "toeing in" when tension is applied to the cord.

Another feature of the invention resides in the anti-fouling guide means particularly associated with the double pulley hanger, the guide means preventing the draw cord from twisting or riding over onto the wrong pulley groove, while at the same time permitting ease of assembly. The guide means are especially adapted for guiding the draw cord from both sides of the pulley so that protection against fouling is provided during both raising and lowering of the shade.

Another objective of the invention has been to provide a guide ramp for that loop of the draw cord which is manually operated to raise and lower the blind, the ramp reducing the fraying of the cord and providing assurance against the inadvertent release of the engagement of the lock dog with the cord.

2

Another feature of the invention resides in the manner in which the lock dog is mounted in its supporting structure as well as the cooperating shape of the supporting structure to facilitate assembly.

5 These and other features of the invention will become more readily apparent from the following detailed description taken in conjunction with the accompanying drawings in which:

FIG. 1 is an elevational view of a slat blind to which 10 pulley hangers of the present invention are mounted;

FIG. 2 is a front elevational view of a single pulley hanger;

FIG. 3 is a front elevational view of a double pulley hanger;

15 FIG. 4 is a side elevational view of a single pulley hanger;

FIG. 5 is a side elevational view of a double pulley hanger;

FIG. 6 is a top plan view partly in section taken along 20 lines 6—6 of FIG. 1;

FIG. 7 is a cross sectional view taken along lines 7—7 of FIG. 4;

25 FIG. 8 is a cross sectional view taken along lines 8—8 of FIG. 5;

FIG. 9 is a cross sectional view taken along lines 9—9 of FIG. 8;

FIG. 10 is a cross sectional view taken along lines 10—10 of FIG. 8; and

30 FIG. 11 is a cross sectional view taken along line 11—11 of FIG. 8.

Referring to FIG. 1, a slat blind 10 is shown as formed with a plurality of slats 11 which are in vertical alignment and are interconnected together by being woven with respect to strings 12. The uppermost slat 13 is folded over on the adjacent slat 14 (FIGS. 4—6) the two slats being secured to a head bar 15 which forms the top of the slat blind. The slats are secured to the head bar by wire staples 16 as illustrated in FIG. 6. At the left side of the slat blind is a single pulley hanger 20 and at the right side of the slat blind is a double pulley hanger 21. A cord 22 passes over the pulleys and is secured at its ends in such a manner as to form a loop 23 around the left side of the slat blind, a loop 24 around the right side of the slat blind and a loop 25 which hangs free 45 for the manual raising and lowering of the blind. The free ends 26 and 27 of the cord 22 are knotted as at 28 and are wrapped about the respective projecting ends of the pulley hangers 20 and 21 in a manner to be described below in order to secure the pulley hangers to the slat blind. The cord is oriented with respect to the slat blind and the respective hanger pulleys as follows:

Beginning with the fixed end 27 at the right side of the blind, the cord passes behind the slat blind to the bottom thereof and upwardly in front of the slat blind to form the loop 24. The cord passes over the outer groove of the double pulley and back over the inner groove to drawing loop 25. The cord then passes over the pulley on the hanger 20, downwardly in front of the slat blind and up in back of the slat blind to form the 60 loop 23, the remaining end 26 being fixed to the hanger 20.

The hanger pulley 20 has a hanger plate 30 (FIGS. 2, 4, 6 and 7) which has a key hole aperture 31 adapted to admit a headed fastener such as a screw or nail through 65 an enlarged portion 32 and to secure the hanger plate to the fastener in the narrower portion 33. The hanger plate 30 has notches 34 in each vertical edge thereof, the notches being positioned immediately adjacent the upper surface of the head bar when the hanger is in its operative position. The construction of the notch is such that a flat edge 35 lies parallel to the surface of the head board, the other side of the slot being formed by a V-shaped

surface 36. The function of the notches 34 is to receive the end 26 of the cord as it is wrapped about the hanger in order to secure the hanger to the head board. The shape of the notches facilitates the introduction of the cord into the notches but serves to prevent the inadvertent removal of the cord from the notches during operation. The lower portion of the hanger plate is horizontally embossed or recessed as at 40 to provide a shoulder 41 against which the headbar 15 bears. A second shoulder 42 of smaller dimension than the shoulder 41 is also formed by the recess 40 to receive a pulley frame 43. Because the shoulder 42 is of smaller dimension than shoulder 41 the inner leg 44 of the pulley frame is, when in position, substantially flush with the surface of the hanger plate 30. The pulley frame 43 is U-shaped and has the leg 44 referred to above and a leg 45. The legs 44 and 45 are apertured as at 46 and 47 and the lower end of the hanger plate 30 is apertured as at 48. A rivet 49 forming the axle shaft of a single grooved sheave or pulley 50 passes through the apertures 46, 47 and 48, through a bore 51 through the center of the pulley to secure the pulley frame to the hanger plate 30, and to form an axle about which the sheave 50 may rotate. It can be seen from FIG. 4 that the axle shaft 49 locks all but pivotal movement of the pulley support 43 with respect to the hanger plate 30 and rotary movement is blocked by the engagement of the shoulder 42 with the corresponding surface on leg 44 of the pulley frame.

When in position on the porch shade the upper edge of leg 45 engages the headbar 15 and confines the cord on the sheave 50. Prior to fixing the pulley hanger on the headbar, however, the cord can merely be laid on the sheave 50 rather than threaded into position.

The double pulley hanger is similarly constructed. As shown in FIG. 3, the double pulley hanger 21 has a hanger plate 60 provided with a keyhole aperture 31 having an enlarged portion 32 and narrow portion 33. Notches 34 are provided in the side edges, the notches 34 being formed by a straight edge 35 and a V-shaped projection 36 all as described above in connection with the single pulley 20.

As best shown in FIG. 5, the hanger plate 60 has a transverse embossment or recess 61 providing a shoulder 62 which bears against the headbar 15 and provides, along with the similar construction of the single pulley, a support for the slat blind. The recess 61 also provides a shoulder 63 of smaller dimension than the shoulder 62 which is in engagement with a similarly shouldered portion 64 on a leg 65 of a generally U-shaped pulley frame 66. The hanger plate 60 has a lower end portion 67 which extends along almost the complete length of the leg 65 thereby providing a double thickness of material which bolsters the pulley against twisting and bending during its use.

A double grooved sheave 70 is mounted on an axle shaft 71 (FIG. 9) constructed by a shouldered semi-tubular rivet passing through apertures 72 and 73 in the legs of the pulley frame and an aperture 74 in the lower end of the hanger plate 60. Both types of pulleys, of course, can be constructed of a single piece for the hanger plate and pulley frame. However, the illustrated two piece construction is preferred because of the extra strength provided by the double thickness at the joint between the two pieces. As in the case of the single pulley hanger 20 the pulley frame is tightly secured to the hanger plate 60 by the axle shaft 71 and the cooperation of the engaged shoulders 63 and 64 of the hanger plate and pulley frame respectively.

Below the apertures 72, 73 and 74 are similar apertures 75, 76 in the pulley frame and 77 in the hanger plate which receive a lock dog 80 having ears 81 and 82 projecting therefrom. The ear 81 projects beyond the surface of the pulley frame so that it is engageable by the assembler to facilitate in the assembly of the device as described below.

As best illustrated in FIGS. 8 and 10, the pulley hanger

plate has a vertical flange 85 which extends between the two legs of the pulley frame and provides a surface against which the lock dog 80 can force the cord portions of loop 25 to lock the cord in position thus fixing the elevated portion of the blind. A tab 86 on a leg 87 of the pulley frame overlies the edge 88 of the tab 86 where it butts against the leg 87 to secure the flange against bending outwardly under the repeated stress of the locking of the cord against its surface. The flange 85 has a dimple 89 which prevents the lock dog 80 from swinging about its pivotal axis to an inoperative position. This dimple assumes its greatest importance during the assembly of the device to be described below. To facilitate the regularity and surety of operation, the lower edge of the flange 85 is depressed inwardly as at ramp 90 to help center the cord 22 and push it against the lock dog 80.

The bight portion 91 of the pulley frame is slotted as at 92 and 93 to provide apertures through which the respective cord portions of the loop 25 passes. The two slots leave a divider 94 which, together with guide means which will be described below, prevent the undesirable twisting of the cord on the double grooved sheave. The portion of slot 92 nearest the locking dog is of a decreased width. The decrease in width tends to retard the movement of the outer cord portion passing therethrough as both cord portions are moved toward the locking dog. This retardation overcomes the natural tendency of the outer cord portion to lead, and thereby effects a more uniform or simultaneous engagement of the two cord portions with the locking dog. Further, the shape of groove 92 guides the cord toward the center of the area of engagement with the dog where the dog more effectively can perform its locking function.

The guide means for the cord is best illustrated in FIG. 5. The outside leg 87 of the pulley frame has an upwardly projecting flange 100 which is offset inwardly so that the lower portion of the flange is in engagement with the rim 101 of the sheave 70. The flange 100 serves in part to center the sheave but more particularly to prevent the cord 22 from riding over the rim and off the sheave. The recess or embossment 61 described above performs the same function for the other side of the sheave.

A second flange 102 projects inwardly and upwardly from outside leg 87 of the pulley frame. That flange serves to confine an inside run 103 of the cord to the inside groove 104 and cooperates with the embossment 61 to keep the run from riding over the rim of the sheave. A lower portion 105 of the flange 102 which presents a surface which is co-planar with the surface of the flange 100 and provides a guide surface for an outside run 106 of the cord 22. That flange portion 105 cooperates with a guide flange 107 projecting from the leg 65 of the pulley frame to guide the outside run of the cord and to prevent it from riding over the rim of its groove and twisting with respect to the inside run. The flange 107 is integral with a bracket 108 having an inclined upper surface 109. The inclined surface together with the pressure exerted on the outside run 106 by the weight of the slat blind roll always urges the outside run 106 toward its proper outside groove and augments the guide flanges described above in maintaining the respective cord runs on their respective grooves and to prevent twisting of the cord runs.

The upper edge of flange 102 in engagement with headbar 15 confines the inner run of the cord on the sheave groove. However, as in the case of the single groove pulley, the cord can be applied merely by laying it over the sheave before the hanger is in position.

The lock dog 80 is best illustrated in FIGS. 8 and 9. It is a U-shaped piece having the ears 81 and 82 described above. The dog has a bight portion 110 having a projecting flange 111 which is formed with a saw tooth edge 112 as shown in hidden lines in FIG. 9. The saw tooth edge bites into the fibers of the cord so

that during locking slippage of the cord in a counter-clockwise direction as viewed in FIG. 8 is prevented. The dimensions of the lock dog should be related to the pulley frame so that in locking the cord is forced against the inner surface of the flange 85 and thereby clamped between that surface and the teeth of the lock dog.

The lock dog has a rearwardly projecting abutment 113 which is engageable with a shoulder 114 formed by the guide flange portion 105. The engagement of the abutment 113 with the shoulder 114 limits the clockwise pivoting of the lock dog (as viewed in FIG. 8) so that the teeth of the lock dog will always overlie a portion of the slots 92 and 93 and be engageable with the cord.

In assembling the invention, particularly the double grooved pulley 21 (similar considerations obtain for the single grooved pulley), the parts are first formed as shown in the drawings, that is, as they will be in their assembled condition, except for the pulley frame. In the formation of the pulley frame 66 the walls 65 and 87 have about a 12° spread with respect to each other. That spread, first, permits the unit to be stripped from the stamping die. Second, in assembly it permits the hanger plate with its flange 85 to be inserted into the assembled position with respect to the pulley frame. Further, it permits the frame to receive the lock dog with its projecting ears 81 and 82 projecting through their associated apertures. When the hanger plate, pulley frame and lock dog are assembled, then the pulley and its axle shaft forming rivet 71 are properly positioned with the rivet 71 passing through the apertures 72, 73 and 74. The walls 65 and 87 are forced together into substantial parallelism and the rivet peened over to complete the assembly of the hanger. When the walls 65 and 87 are forced together the flange or lock wall 85 prevents the walls from being forced beyond a condition of parallelism.

In threading the cord into the pulley frame and around the pulley, it is important for rapid assembly operation that the lock dog be maintained in its proper position out of interference with the cord. If the lock dog swings counterclockwise as viewed in FIG. 8 to an extreme upward position against the pulley, the assembler will be required to take an extra step to shake the lock dog down into the proper position. Also, as the cord is being threaded through the frame the threading operation will be greatly impeded by the cord snagging on the teeth of the lock dog. To obviate these obstacles to rapid assembly, two structural measures are taken. First, the dimple 89 is provided in flange 85. The dimple 89 assures the maintenance of the lock dog in the proper lower position. Second, the lock dog ear 81 projects outside of the pulley frame so that it is actuatable by the assembler. By manipulating the ear 81 with this thumb the assembler can swing the lock dog to a rearward position and hold it in that position until the cord threading operation is completed.

In operation the home owner will normally purchase a completely assembled slat blind having the pulley hangers properly inserted between the headbar 15 and the adjacent slat 14 with the cord ends wrapped about the hanger plates 30 and 60. As indicated above, the cord ends are quickly assembled in this position by knotting the ends as at 28, and wrapping about the hanger plates in the slots 34. As appears from FIG. 4 for example, when the cord is properly positioned in slots 34, the cord forms two bearing locations for the hanger against the upper surface of the headbar 15. Similarly, the lower surface of the headbar is engaged by the shoulder 41 or 62 of the two types of pulleys respectively. The combination tends to form a clamp on the headbar to prevent the twisting or toeing in of the pulleys.

The particular structure to which the slat blind is to be mounted may not lend itself to the manufacturer's positioning of the hanger pulleys. That position can easily be changed merely by removing the cord ends

from the slots 34 withdrawing the hanger plates from between the headbar and adjacent slat and respositioning the hanger plates in the desired location. Precise positioning is not required for even when in the condition illustrated in FIG. 1, the plates are slidable an inch or so in either direction as permitted by the location of the staples 15.

After the screws are mounted in the supporting structure, the slat blind is positioned on the supporting structure by passing the keyhole apertures 31 over the heads of the screws and permitting the slat blind to drop to lodge the screw shanks in the narrow portions 33 of the keyhole slots.

In pulling on loop 25 to raise the blind, and in releasing the dog 86 and raising the cord loop 25 to lower the blind, the guiding members described above maintain the cords in proper operative orientation. Even in the first operation, the guiding members will have kept the cords in proper orientation so that there is no requirement for readjustment of the cords after the blind is received from the manufacturer in order to render the slat blind operative.

The ramp 90 serves two functions in the operation of the invention. It is seen that from FIG. 11 that the ramp 90 overlies the cord slots 92 and 93. In pulling down on the cord the ramp 90 provides a smooth ramp guiding the cords through the cord slots 92 and 93 thereby preventing fraying of the cord. Further, from time to time, a person will lift the rolled bundle of blind slats removing the tension from the cord loop 24. Under this condition there may be greater weight on cord loop 25 which would tend to free the lock dog from its engagement with the cord so that when the bundle is released the blind would go plunging to the floor. The ramp 90 tends to urge the cord toward the lock dog under such conditions and eliminates the possibility of inadvertent release of the lock dog. Release of the lock dog can be effected, then, only when the cord is pulled by the operator.

I claim:

1. A hanger pulley comprising an upper plate, a U-shaped frame having a pair of spaced vertical legs at the lower end of said plate, a double grooved sheave rotatably mounted in said frame to receive two runs of a cord, the outer run making a 180° turn about said sheave and the inner run making a 90° turn about said sheave, guide flanges projecting laterally from each said vertical leg to confine said outer run to its groove and a guide flange projecting upwardly a substantial distance above said sheave and centrally of said sheave and on the side of said sheave from which the inner run leaves the top of said sheave to cooperate with said frame in confining said inner run to its groove.

2. A hanger pulley comprising, an upper plate, a U-shaped frame having a pair of spaced vertical legs at the lower end portion of said plate, a double grooved sheave rotatably mounted in said frame to receive two runs of a cord, the outer run making a 180° turn about said sheave and the inner run making a 90° turn about said sheave, guide flanges projecting laterally from each said vertical leg to confine said outer run to its groove, the guide flanges projecting from the inner leg of said frame being formed by a bracket having a downwardly and centrally inclined surface terminating in a guide flange, said downwardly inclined surface urging said outer cord run onto its respective groove, and a guide flange projecting upwardly and centrally of said sheave to cooperate with said frame in confining said inner run to its groove.

3. A cord pulley hanger in combination with a slat blind porch shade having a head bar and an upper slat secured to the surface of said head bar, said hanger comprising a plate portion inserted between said head bar and slat, a slot on each longitudinal edge of said plate immediately above said head bar, said slots receiving a cord thereby blocking said hanger from dropping from between said head bar and upper slat.

4. A cord pulley hanger in combination with a slat blind porch shade having a head bar and an upper slat secured to the surface of said head bar, said hanger comprising a plate portion inserted between said head bar and slat, a slot on each longitudinal edge of said plate immediately above said head bar and receiving a cord to secure said hanger on said head bar, said slots being formed by a straight lower edge normally parallel to said head bar and a U-shaped re-entrant upper edge, whereby to facilitate application of a cord into said slot and to impede inadvertent removal of said cord from said slot.

5. A cord pulley hanger in combination with a slat blind porch shade having a head bar and an upper slat secured to the surface of said head bar, said hanger comprising a plate inserted between said head bar and slat, a shoulder on said plate in engagement with the lower surface of said head bar when said plate is inserted in operable position, a slot on each longitudinal edge of said plate immediately above said head bar, said slots snugly receiving a cord thereby confining said head bar between said cord and hanger.

10 6. In a slat blind porch shade having a head bar and

15 an upper slat secured to the surface of said head bar inserted between said slat and said head bar, a hanger pulley comprising an upper plate, a U-shaped frame having a pair of spaced vertical legs at the lower end of said plate, a double grooved sheave rotatably mounted in said frame to receive two runs of a cord, the outer run making a 180° turn about said sheave and the inner run making a 90° turn about said sheave, guide flanges projecting laterally from each said vertical leg to confine said outer run to its groove and a guide flange projecting upwardly a substantial distance above said sheave and terminating adjacent said head bar, said flange being located centrally of said sheave and on the side of said sheave from which the inner run leaves the top of said sheave to cooperate with said frame and head bar in confining said inner run to its groove.
